UNITED STATES PATENT OFFICE.

SETH H. SMITH, OF DELTA, OHIO, ASSIGNOR TO THE SMITH MANUFACTURING COMPANY, OF SAME PLACE.

MACHINE FOR CUTTING WOODEN PLATES.

SPECIFICATION forming part of Letters Patent No. 276,198, dated April 24, 1883.

Application filed January 27, 1883. (No model.)

To all whom it may concern:

Be it known that I, SETH H. SMITH, a citizen of the United States, residing at Delta, in the county of Fulton and State of Ohio, have 5 invented a new and useful Machine for Cutting Wooden Plates, of which the following is a specification, reference being had to the accompanying drawings.

This invention relates to a machine for cutting continuously from a block of wood concavo-convex shells, plates, or dishes, serving as packages for butter, berries, and for other purposes; and my invention consists in certain improvements in the construction of the 15 said machine, which will be hereinafter fully described, and particularly pointed out in the claims.

In the drawings hereto annexed, Figure 1 is a perspective view of my improved machine. 20 Fig. 2 is a side view of the same. Fig. 3 is a front view. Fig. 4 is a top plan. Fig. 5 is a longitudinal vertical sectional view. Fig. 6 is a detail view in perspective of the feed mechanism. Fig. 7 is a detail view of the front end 25 of the follower, showing the mechanism for holding the block of wood in position for operation. Fig. 8 is a detail view of the mechanism for connecting the feed-screw with the follower, and Fig. 9 is a detail view of the stop 30 mechanism.

The same letters refer to the same parts in all the figures of the drawings.

The frame of my improved machine consists essentially of a box or trough, A, mounted or 35 supported upon suitable legs or standards, B. At the front end of the box A bearings are provided for the transverse main shaft C, carrying a band-wheel, D, to which motion may be transmitted from any suitable motive power. 40 The main shaft is provided in front of the box A with hubs or collars E E, to which a curved knife or cutter, F, is securely attached. One side of the box A has bearings for a longitudinal shaft, G, the front end of which has a bevel 45 gear or pinion, H, engaging a like pinion, I, upon the end of the main shaft C. J is a hub or collar secured upon the shaft G in rear of the pinion H, and having an arm, K, to which a straight radial knife or cutter, L, is bolted 50 or otherwise secured. This cutter, when the

shaft G revolves, moves directly in front of and almost in contact with the front end of the box A. A horizontal U-shaped bracket, M, is provided, forming a guard for the knife L. 55 N is a follower, sliding longitudinally in the trough A. The said follower consists of a box, upon the inner side of the front end of which is pivoted a disk, O, having an upwardly-projecting arm or lever, P, by means of which it may be oscillated upon its pivot. The front 60 end of the box has bearings for two laterally-sliding arms or dogs, the outer ends of which have inwardly-turned sharp hooks Q, while the inner ends of the said dogs, which are denoted by letter R, are provided with pins S, extending through slots T in the front end of the box or follower and into eccentric slots U 65 formed in the disk O.

It will be seen that by turning the said disk the dogs S may be moved apart, so as to release, or together, so as to clamp and hold the block of wood to be cut, which has been previously placed in the trough A, in which it should as nearly as possible fit. To receive the ends of the dogs S, slots or grooves V may 70 be formed in the inner sides of the box.

The rear end of the follower-frame is provided with a slot, W, in which are placed two vertically-sliding half-nuts, X X, having pins Y Y, which engage eccentric slots Z Z in a 75 plate, A², pivoted to the end of the box or frame, and having an operating-handle, B². C² is a feed-screw placed longitudinally in the trough A and journaled in the rear end of the latter and in a bracket, D², about centrally in 80 the same. The feed-screw passes through the slot W of the follower, between the nuts X X, which, by the mechanism described, may be thrown into engagement with or released from the feed-screw by simply operating the lever 85 B². The rear end of the feed-screw projects through the rear end of the trough A and carries a ratchet-wheel, E². Upon the rear end of trough A, surrounding the end of the screw, is formed a collar, F², upon which is journaled 90 a hub, G², having arms H² I², the former of which carries a spring-pawl, J², engaging the ratchet-wheel E². The arm I² has a slot, K², radial to the hub, in which a wrist-pin, L², is 95 adjustable by means of a thumb-nut or in any 100

suitable manner. The pin L^2 is connected by a pivoted rod, M^2 , with a similar wrist-pin, N^2 , radially adjustable in a slot, O^2 , formed in a disk, P^2 , secured upon the rear end of the shaft 5 G. It will thus be seen that when the latter revolves the disk P^2 imparts an oscillating motion to the hub G^2 and its attachments, which in turn through the pawl J^2 serves to revolve the feed-screw, thereby feeding the follower 10 forward in the box A. The length of the feed may be determined by adjusting the wrist-pins in their respective slots. To move the follower back it is only necessary to disengage the half-nuts from the feed-screw by the mechanism described. 15

The band-wheel D, which is loose upon the main shaft, may be thrown into gear with the latter by a clutch, Q^2 , sliding upon the said shaft. The clutch is operated by a lever, R^2 , 20 mounted upon a vertical pivot adjoining the box or trough A. The rear end of said lever rests upon a horizontal arm, S^2 , extending from a vertical shaft, T^2 , journaled to the side of the box or trough A. The arm S^2 is provided 25 with upwardly-projecting pins U^2 , between which the lever R^2 rests. The shaft T^2 is provided at its upper end with an inwardly-projecting arm, V^2 , adapted to be engaged or struck by a stop, W^2 , longitudinally adjustable 30 upon the upper edge of the follower. This stop may be set or adjusted so as to stop the machine when the follower reaches any desired point which may be previously determined. When the stud or stop W^2 strikes the arm V^2 35 it turns the shaft T^2 , thereby operating the lever R^2 and throwing the clutch out of gear, thus stopping the machine.

The U-shaped bracket M, which has been hereinbefore described as forming a guard for the knife L, also performs an important function in forming one of the bearings for the main shaft C, one end of which is journaled in a box, X^2 , upon the front arm of said U-shaped bracket. Said arm, which is denoted by letter Y^2 , is connected by a brace, Z^2 , with one of the supports of the machine, thus holding the machine steady and without trembling during operation.

The operation of my improved machine will 50 be readily understood from the foregoing description, taken in connection with the drawings hereto annexed. After moving the follower back, a block of wood of the proper size is placed in the trough A and clamped by the dogs R. When the machine is started the block is fed to the knives or cutters, which are to be so arranged in relation to each other and to the feed that the feed shall take place after the curved knife completes its passage 55 across the face of the block and before the knife L reaches the edge of the same, while the latter must nearly or quite complete its throw before the cutting-knife F comes into action. The function of the latter is to cut from the face of the block shells or concavo-convex 60 dishes, while the radial knife L, before each throw of the cutting-knife F, faces off the

block, thus causing the knife F to cut always from the face of the block, and making all the shells cut off exactly the same size and shape. 70 In cross-section the said shells are naturally segmental, while in longitudinal section their shape is governed by that of the knife or cutter F. When the block has been cut up, or at any desired point, the machine is automatically stopped by the mechanism described, and the butt-end may then be removed, the follower moved back, and a new block placed 75 in position for operation.

I am aware that a clutch serving to connect a drive-wheel to a shaft has been arranged to be operated by the action of a follower upon the lever holding the said clutch, and such mechanism I do not broadly claim. 80

I claim as my invention and desire to secure by Letters Patent of the United States— 85

1. A machine for cutting concavo-convex shells continuously from a block of wood, the same comprising in its construction a revolving curved knife having both its ends attached to the driving-shaft, and a facing-knife attached radially to a shaft located at an angle to the driving-shaft, substantially as set forth. 90

2. In a machine for cutting concavo-convex shells continuously from a block of wood, the combination of a revolving curved knife having both its ends attached to the driving-shaft, a facing-knife attached radially to a shaft located at an angle to the driving-shaft, 100 and mechanism for feeding a block intermittently to the said knives after the throw of the cutting-knife and before the throw of the facing-knife, substantially as set forth. 95

3. The combination of the frame-box having a collar upon its rear end, the feed-screw journaled longitudinally in said frame-box, projecting through said collar and carrying a ratchet-wheel, a hub mounted upon the said collar and having two arms, one of which carries a spring-pawl engaging the ratchet-wheel, while the other has a radially-adjustable wrist-pin, a disk mounted upon a shaft parallel to the feed-screw and having a radially-adjustable wrist-pin, a pivoted rod connecting the two 110 wrist-pins, and suitable operating mechanism, substantially as and for the purpose set forth. 115

4. The combination of the main shaft, the band-wheel mounted loosely upon the same and having a clutch, a clutch-collar sliding 120 upon the shaft, a horizontal lever operating the said clutch-collar, a vertical shaft having at its lower end an arm supporting the rear end of the lever between two vertical pins and at its upper end an inwardly-projecting arm, 125 and the follower having a longitudinally-adjustable stop-stud, substantially as set forth.

In testimony that I claim the foregoing as my own I have hereto affixed my signature in presence of two witnesses.

SETH H. SMITH.
